CLAIM

The ornamental design for a car adapter, as shown and described.

DESCRIPTION

FIG. 1 is a top front right perspective view of a car adapter showing my new design;

FIG. 2 is a bottom rear left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion of the claimed design shown in FIG. 1; and,

FIG. 10 is an enlarged view of a portion of the claimed design shown in FIG. 2.

The dash-dot broken lines immediately adjacent the shaded areas represent an unclaimed boundary between claimed and unclaimed surfaces. The dash-dash broken lines represent portions of the car adapter that form no part of the claimed design. None of the broken lines forms any part of the claimed design.
